M. F. WIELAGE,
DIRIGIBLE SPOTLIGHT.
APPLICATION FILED FEB. 4, 1921.

1,434,468.

Patented Nov. 7, 1922.

Inventor
Marcus F. Wielage
by Wm. H. Monroe
Attorney

UNITED STATES PATENT OFFICE.

MARCUS F. WIELAGE, OF CLEVELAND, OHIO.

DIRIGIBLE SPOTLIGHT.

Application filed February 4, 1921. Serial No. 442,390.

To all whom it may concern:

Be it known that I, MARCUS F. WIELAGE, a citizen of the United States, and resident of Cleveland, in the county of Cuyahoga and State of Ohio, have invented certain new and useful Improvements in Dirigible Spotlights, of which I hereby declare the following to be a full, clear, and exact description, such as will enable others skilled in the art to which it appertains to make and use the same.

The objects of the invention are to provide a simple, efficient and practical form of adjustable support for a dirigible spot light for a motor car, by means of which the lamp can be revolved, upon vertical and horizontal axes, to direct its rays in any required direction.

This support is so constructed and positioned that the lamp can be adjusted by the operator without leaving his seat in the car, and without exposure to the elements when the sides of the car are enclosed. Also all movements of the lamp can be controlled from one operating point, and the lighting switches can also be operated simultaneously therewith.

In this manner all the necessary movements required for lighting and operating the lamp can be performed with one hand from within the car.

A further advantage is provided by the perfect insulation afforded to the conduction wires for the lighting current, which are always enclosed in tubular guides, which prevents frictional contact of the moving parts of the device.

The invention is hereinafter described, illustrated in the accompanying drawings, and specifically pointed out in the claims:—

In the accompanying drawings, Fig. 1 is a horizontal section of the device; Fig. 2 is a vertical section thereof; Fig. 3 is a bottom plan thereof; Fig. 4 is a transverse section of the lamp support, on line *a—a*, Fig. 1; Fig. 5 is a transverse section, on line *b—b*, Fig. 1; Fig. 6 is a horizontal section, similar to Fig. 1, showing a modified clamping means.

In these views, A represents a standard, supporting the wind shield or canopy of the car.

B and C are concentric outer and inner tubular shafts which pass through the

standard, the inner shaft preferably finding its bearing upon the outer shaft.

D is a bearing in which the outer shaft is secured in such a manner as to permit free rotation thereof, but to prevent longitudinal movement. This bearing is secured by means of the clamping nut, E, upon the inner portion of the bearing, a shoulder, F, upon the outer end of the aforesaid bearing, and the outer shaft is secured in the bearing by means of the shoulder, G, upon an elbow, H, upon the inner extremity of said outer shaft, and nuts, I and J, upon the outer portion thereof. Spring washers, K, K, permit making a close but resilient joint between the moving and stationary parts.

Upon the outer end of the outer shaft is secured the split elbow, L, or curved continuation of the shaft. Screws, M, M, secure the parts together. Upon this elbow is pivoted the lamp, M', upon the hollow stem, N, to which a bevel gear, O, is secured.

To the outer end of the central hollow shaft is secured a similar bevel gear, P, so that by revolving the central shaft the lamp can be horizontally rotated upon its vertical axis.

Also when the outer hollow shaft is revolved in the bearing, the lamp will revolve about the horizontal axis of the aforesaid shaft.

To make it possible to revolve these shafts independently from within the enclosure of the car, the split elbow, L, or connection H, is secured to the inner end of the outer shaft.

Revolvably secured in the outer extension, R, of this elbow, is shown the short shaft, S, to the inner end of which is secured the bevel gear, T, which intermeshes with the bevel gear, V, upon the inner hollow shaft, C. A set screw S', entering a groove, S", in this shaft, retains the shaft in place and permits adjustment to make the shaft loose or tight in its bearing, and prevents the lamp from being moved by the vibration of the car.

A knurled knob, W, upon the outer end of this short shaft permits revolving the shaft, the inner shaft, and the stem upon which the lamp is mounted, thus enabling the operator to revolve the lamp upon its vertical axis.

Also the outer shaft can be revolved on its horizontal axis without removing the fingers

from the laterally projecting portion, R, of the member H, which can be used as an arm, thus enabling the operator to swing the lamp to any vertical angle desired, without leaving his seat, by a motion of the wrists.

5 The tubular inner shaft permits of the introduction of insulated conductor wires, X, X, without difficulty, to the base of the lamp, and a short tubular elbow, Y, connects the inner tubular shaft with the hollow lamp stem, and prevents the abrasion of the insulation from contact with the bevel gears in the elbow, L. Any ordinary switch, as at X', can be used for closing the electric 10 circuit.

In Fig. 6, a simple form of bearing is shown where the sleeve bearing is dispensed with and a shoulder, Z, and nuts, Z', Z', upon the outer shaft, secure it revolvably in place.

20 Plates, Z², Z², can be employed where the standard is made of wood.

This construction is used when the standard is too narrow to permit of the use of the bearing sleeve.

25 Having described the invention, what I claim as new, and desire to secure by Letters Patent, is:

1. In a dirigible lamp, in combination, a standard, concentric hollow shafts passing 30 through said standard, said outward shaft provided with an upwardly turned outer end, and a laterally turned inner end, a lamp provided with a hollow stem, vertically pivoted upon the upwardly curved outer end of 35 said outer shaft, and engaging gears upon the adjacent ends of said hollow stem and inner shaft, a shaft within the laterally turned inner end of said outer shaft, gearing connecting the adjacent ends of said last mentioned shaft and central shaft, and means 40 for rotating the same independently of the outer shaft, to revolve said lamp on its vertical axis, the aforesaid laterally turned inner end of said outer shaft serving as an arm 45 for rotating said outer shaft, and said lamp, on its horizontal axis.

2. In a dirigible lamp, in combination, a standard, concentric hollow shafts passing through said standard, said outward shaft 50 provided with an upwardly turned outer end, and a laterally turned inner end, a lamp provided with a hollow stem, vertically pivoted upon the upwardly curved outer ends of said outer shaft, and engaging gears upon 55 the adjacent ends of said hollow stem and

inner shaft, a shaft within the laterally turned inner end of said outer shaft, gearing connecting the adjacent ends of said last mentioned shaft and central shaft, and means for rotating the same independently 60 of the outer shaft, to revolve said lamp on its vertical axis, the aforesaid laterally turned inner end of said outer shaft serving as an arm for rotating said outer shaft, and said lamp, on its horizontal axis, and 65 flexible conductors for the lighting current passing through said hollow inner tube and stem.

3. In a dirigible lamp, in combination, concentric hollow outer and inner shafts, 70 said outer shaft provided with an upwardly turned extension at the outer end, and a laterally turned extension at the inner end, a lamp pivoted upon the said outer extension of said outer shaft, a shaft revolvable in said 75 inner extension, geared connection between said inner shaft and said shaft in said inner extension, and between said shaft and said lamp, a support through which said outer and inner shafts pass, and clamping means 80 on said outer shaft, said clamping means permitting rotation of said outer shaft, but adapted to prevent longitudinal movement thereof.

4. In a dirigible lamp, in combination, concentric hollow outer and inner shafts, said outer shaft provided with an upwardly turned extension at the outer end, and a laterally turned extension at the inner end, a lamp pivoted upon the said outer extension 90 of said outer shaft, a shaft revolvable in said inner extension, geared connection between said inner shaft and said shaft in said inner extension, and between said shaft and said lamp, a support through which said 95 outer and inner shafts pass, and clamping means on said outer shaft, said clamping means permitting rotation of said outer shaft, but adapted to prevent longitudinal movement thereof, frictional means for controlling the rotation of the lamp on its horizontal axis, and frictional means for controlling its rotation on its longitudinal axis. 100

In testimony whereof, I hereunto set my hand this 28th day of January, 1921.

MARCUS F. WIELAGE.

In presence of—
W.M. M. MONROE,
CHAS. C. GOLDMAN.

DISCLAIMER

1,434,468.—*Marcus F. Wielage, Cleveland, Ohio. DIRIGIBLE SPOTLIGHT. Patent dated November 7, 1922. Disclaimer filed June 15, 1932, by the assignee, International Spotlight Corporation.*

Hereby enters this disclaimer to that part of the claims in said specification which are in the following words, to-wit:

“1. In a dirigible lamp, in combination, a standard, concentric hollow shafts passing through said standard, said outward shaft provided with an upwardly turned outer end, and a laterally turned inner end, a lamp provided with a hollow stem, vertically pivoted upon the upwardly curved outer end of said outer shaft, and engaging gears upon the adjacent ends of said hollow stem and inner shaft, a shaft within the laterally turned inner end of said outer shaft, gearing connecting the adjacent ends of said last mentioned shaft and central shaft, and means for rotating the same independently of the outer shaft, to revolve said lamp on its vertical axis, the aforesaid laterally turned inner end of said outer shaft serving as an arm for rotating said outer shaft, and said lamp, on its horizontal axis.

“2. In a dirigible lamp, in combination, a standard, concentric hollow shafts passing through said standard, said outward shaft provided with an upwardly turned outer end, and a laterally turned inner end, a lamp provided with a hollow stem, vertically pivoted upon the upwardly curved outer ends of said outer shaft, and engaging gears upon the adjacent ends of said hollow stem and inner shaft, a shaft within the laterally turned inner end of said outer shaft, gearing connecting the adjacent ends of said last mentioned shaft and central shaft, and means for rotating the same independently of the outer shaft, to revolve said lamp on its vertical axis, the aforesaid laterally turned inner end of said outer shaft serving as an arm for rotating said outer shaft, and said lamp, on its horizontal axis, and flexible conductors for the lighting current passing through said hollow inner tube and stem.”
